The diagram illustrates a bridge pier foundation. It features a stepped spread footing with a central pile foundation. The spread footing is shown with a stepped profile, and the central pile foundation is depicted as a vertical column. The entire foundation is situated on a bedrock layer, indicated by a hatched pattern at the bottom.

BELT SANDER

John W. Edgemond, Jr., Los Altos, and John J. O'Connor, Palo Alto, Calif., assignors to Magna Power Tool Corporation, a corporation of California

Application November 4, 1955, Serial No. 544,996

10 Claims. (Cl. 51—135)

This invention relates to belt sanders and particularly to belt sanders which are adapted to be used in wood and metal working operations.

Belt sanders and, of course, the belt sanding operation, are old, and are well known to those skilled in wood and metal working. The advantages and defects of belt sanders are also well known and need no particular explanation. However, certain of the defects in conventional belt sanders have hampered or limited the operation and use of devices of this kind and it is our object to make an improved belt sander in which certain of the disadvantages of prior devices are eliminated and overcome.

In the past, for example, where belt sanders have been used, it has been considered desirable to permit the same to be positioned in a variety of working positions and generally these devices have been mounted in such a manner that they may be swung from the position in which the sanding surface is substantially horizontal to a position in which the sanding surface is vertical.

It is an object of this invention to provide a new trunnion lock bolt wherein the apparatus is adjustable from one position to another independent of the tension of the locking device.

It is an object of this invention to provide means for eliminating over-loosening of the trunnion with resulting slippiness between the rigid base and the movable sander when the locking member is released to permit movement of the sander with respect to the base.

Substantially all belt sanders have a table-like support immediately underlying the sanding belt and in some prior constructions, dust has tended to accumulate in the sanding surface of the belt and decrease the efficiency of the belt.

It is an object of this invention to provide a table which underlies the upper or operating run of the sanding belt and to provide therein a plurality of recessed portions, because we have found that when a belt passes over an area of non-support the dust tends to be discharged.

Prior belt sanders have also provided a table on or against which the work piece may be supported.

It is an object of this invention to provide a table which also operates as a fence and which may be set at selected positions across the operating surface of the belt or which may be placed on either side thereof. Moreover, we have provided a table which not only acts as a fence, but have provided a means therefor to accommodate either a single or double mounting.

It has, of course, always been necessary to provide some means of mounting the endless belt upon the device and maintaining proper tension upon the belt once it has been loaded.

It is an object of this invention to provide an automatic tensioning device in connection with one of the pulleys which is independent from the belt tracking adjustments whereby the belt will always be kept in proper tension and also for the purpose of permitting substantially in-

2

stantaneous removal and replacement of the sanding belt without affecting tracking adjustments. Such a tensioning device is also desirable to prevent overloading of the drive and to compensate for different lengths of original belts and differences in stiffness and flexibility as each belt is used.

Other objects and advantages of our invention will appear from the following specification taken in conjunction with the accompanying drawings in which:

10 Figure 1 represents a view of our belt sander mounted in substantially vertical position upon the end of the Combination Power Tool disclosed in Edgemond et al. application, Serial No. 494,468 on March 15, 1955;

15 Figure 2 represents an enlarged cross-sectional detail taken along the line 2—2 of Figure 1 and illustrates the means of holding the two side frame members of our device in predetermined spaced relationship;

20 Figure 3 is an enlarged cross-sectional detail taken along the line 3—3 of Figure 2 and illustrates the manner in which the table which supports the upper or operative run of the sanding belt is secured to the frame;

25 Figure 4 is a side view of our belt sander in vertical operating position and illustrates, in dotted line position, the general position of the same when in horizontal operating position;

30 Figure 5 is a fragmentary view of the upper end of the belt sander when in vertical position with the belt removed showing the table which supports the operating run of the sanding belt and also partially showing the idler pulley over which the sanding belt passes and which is maintained under constant automatic tension;

35 Figure 6 is a fragmentary cross-sectional detail taken along the line 6—6 of Figure 4 and illustrates the automatic tensioning device and the means for mounting the idler pulley;

Figure 7 is a cross-sectional detail taken along the line 7—7 of Figure 6;

40 Figure 8 is a cross-sectional detail taken along the line 8—8 of Figure 6 and illustrates the construction of the control knob and ratchet release mechanism for the automatic tensioning mechanism illustrated in Figure 6;

45 Figure 9 is a side view of our sander showing the same in horizontal working position;

Figure 10 is a view, partly in cross-section, taken along the line 10—10 of Figure 9 and showing the drive pulley over which the sanding belt is raised; and

50 Figure 11 is an enlarged view of the trunnion lock bolt mechanism.

As indicated particularly in Figure 1, our device is 50 adapted to be mounted upon one end of the Combination Power Tool disclosed particularly in Edgemond et al., Serial No. 494,468 filed March 15, 1955. While this tool illustrates a preferred environment and mounting, it must be understood that our device may be mounted for 55 separate operation upon a stand of its own and be driven with an independent motor.

As is pointed out in the above identified Edgemond et al. application, the combination tool includes a pair of opposed identical stool bench ends 10 and 11 which support castings 12 and 13. The castings 12 and 13 accommodate parallel longitudinally extending tubes 14. The tubes 15 are supported at one end by a casting 13 and at their other ends are supported by a casting 12a which may be clamped to casting 12 thereby providing a sturdy rigid bench or supporting member.

60 The end casting 12 is provided with a pair of parallel spaced vertical sockets which are adapted to receive a pair of spaced parallel mounting tubes 16 and 17 whose other ends are received in similar recesses in a member 65 18 which forms the mounting base for our belt sander.

The parallel tubular ways 15 provide a mounting for a headstock member indicated generally at 19 which sup-

ports an electric motor which is operatively connected to the power take-off shafts 21, 22 and 23, each of whose purposes has been previously described in the aforementioned Edgemond et al. application. We provide a driven shaft 24 which is adapted to be coaxially aligned with the power take-off shaft 23 and to be operatively connected thereto by means of a coupling member 26.

It is apparent that our device can be suitably mounted in any suitable base which is provided with spaced parallel cylindrically shaped sockets which are adapted to accommodate the mounting tubes 16 and 17 and which is further provided with a motor and means for operatively connecting the same to the driven shaft 24.

Generally speaking, our sander consists of a base member 18 to which a side frame member 27 is pivotally secured by means of an arcuate trunnion construction illustrated in Figures 9, 10 and 11. Similar member 28 is secured in spaced parallel relationship to member 27 which forms another side member of the frame assembly 29 of our device. The frame assembly 29 supports a generally cylindrical driving pulley 31 and a driven adjustable pulley 32 over which a sanding belt 33 may be positioned. The frame assembly 29 also supports the fence or table assembly 34.

As indicated particularly in Figures 2 and 6, the side frame members 28 and 27 are held in predetermined spaced relationship by a pair of tubular spacers 36, only one of which is shown, and a pair of bolts 37. Members 27 and 28 are provided with machined shoulders against which the tubular spacers 36 abut. The head of the bolt 37 and the nut 38 engage the members 27 and 28 and complete a rigid frame assembly 29 for our sander.

The frame assembly 29 is pivotally mounted on the base 18 in the following manner: Member 18 is provided with an arcuate slot 42, which accommodates an insert 44. The exposed face of insert 44 forms an arcuate slot in which arcuate plate 46 is radially slidably as shown in Figures 9 and 11. Plate 46 is maintained in fixed position on the frame member 27.

The frame member 27 has a flattened hole to accommodate and key a bolt 47. Base 18 and insert 44 are provided with an arcuate slot 48 in which the bolt 47 slides as the sander is swung about the axis of the shaft 24. The bolt 47 is threaded at 49 and is provided with a washer 51 and a tension nut 52. Its other end is also threaded and is provided with milled flats fitted to washer 53 and flattened hole in frame assembly 29. A similarly threaded knob 57 completes the assembly.

Operation of the trunnion lock bolt device may briefly be described as follows: The nut 52 is customarily tightened to a point at which the washers 51 and 53 frictionally engage the cooperating surfaces of the base 18 and the frame 29. When the knob 57 is loosened it will become disengaged from the washer 53 and, since the nut 52 is adjusted to provide only light frictional engagement of the washers 51 and 53 with the members 18 and 29, our belt sander may be swung from vertical to horizontal position and back about the axis of the member 24 on the trunnion and track assembly previously described, without members 18 and 27 separating excessively. When our sander is in the desired position, however, the member 57 may be rotated into engagement with the washer 53 thereby increasing the frictional engagement of the washer 53 and the member 29 so that the same will be held in that position. As previously pointed out when the member 57 is retracted and no longer engages the washer 53 our sander may be swung to another desired position. Once the member 57 and the washer 53 are in tight frictional engagement, however, movement of our device is prevented.

The lower ends of the frame members 27 and 28 support roller bearing assemblies 58 and 59 which accommodate the driven shaft 24 upon which the driving pulley 31 is mounted. The driving pulley 31 may be secured to the shaft 24 in any suitable manner as by being keyed

thereto, for example. As indicated in Figures 1 and 10 the shaft 24 is exposed to both sides of the device and is adapted to be driven from either end.

The frame members 27 and 28 also support a table-like member 61 which is secured to them along its side edges and which, as viewed in Figures 2 and 5, is provided with spaced grooves 62. The member 61 forms a support immediately underlying the upper or operating run of the sanding belt 33. The slots or grooves 62 provide areas of non-support under the belt and dust which would normally accumulate in the grits of the belt is discharged therefrom by flexing of the belt at those non-support areas.

The side frame members 27 and 28 are also provided with a plurality of sockets 63, 64, 66, and 67. As illustrated particularly in Figures 1, 9, and 10, the sockets 63 and 64 are adapted to receive mounting tubes 68 and 69 of our table construction. The sockets 66 and 67 are adapted to receive the tubes 68 and 69 in the same manner. However the pairs of sockets 63 and 66 and 64 and 67 in the side frame members 27 and 28 are also spaced the same distance apart and are adapted to receive the mounting tubes 68 and 69 so that our table assembly 34 may operate as a fence as shown in Figure 1.

The tubular members 68 and 69 are adapted to be held in the respective pairs of sockets in any suitable manner, and, for example, I have shown them held by means of threaded members 71 which cooperate with threaded orifices in the frame members 27 and 28 and which are adapted frictionally to engage the members 68 and 69 and hold them in pre-determined position in the selected socket.

The tubular members 68 and 69 support a cross head member 72 to which a table 73 is pivoted at point 74. The member 72 is also provided with a pair of parallel extending arms 76 and 77 which accommodate a cross bolt 78. Adjusting arms 79 and 81 which are pivotally connected to the table 73 at 82 are provided with slots 83. Cross bolt 78 passes through the slots 83. The bolt head 84 of the cross bolt 78 engages in slot 83 in member 81 and the adjustable nut 86, having a handle 87, the nut 86 being threadedly mounted upon the cross bolt 78, releasably engage the arms 79 and 81. Thus, when the table 73 is pivoted about point 74, it may be retained in any predetermined position when the nut 86 is tightened. It is apparent, therefore, that the table 73 may be swung to any of a number of positions as, for example, the position illustrated in Figure 4 to a vertical position as illustrated in Figure 9. It may be swung to either position while it is being utilized as a table as indicated in Figures 4 and 9 or as it is being used as a fence as indicated generally in Figure 1.

Operation of the table fence may briefly be described as follows: When the operator has determined whether the device is to be operated as a table or a fence he positions the mounting tubes 68 and 69 in the appropriate sockets 63, 64, 66 and 67. The members 71 are then tightened so that the tubular members 68 and 69 are locked in a predetermined position to properly space the table 73 from the upper run of the belt 33. The table members 73 may be pivoted about the point 74 to a desired angle with respect to the upper run of the belt 33 when the nut 86 is loosened so that the members 79 and 81 are free to slide with respect to the bolt 78. However when the member 86 is tightened the member 73 will be retained in that predetermined fixed position. The proper positioning of the member 73 away from or toward the upper or operating run of the belt 33 may, of course, be determined by moving the entire assembly upwardly or downwardly with respect to the frame 29. When the desired location has been reached the member 71 may be tightened. The entire assembly can be removed from the device when desired.

The means for retracting the driven pulley 32 so that a belt 33 may be removed therefrom and a new belt positioned thereon is illustrated particularly in Figures 6, 7

and 8. These figures also illustrate the automatic tensioning means which urges the pulley 32 upwardly, as viewed in Figure 6, whereby proper tension may be maintained on the belt 33.

As shown in Figures 6 and 7 the side frame members 27 and 28 are provided with identical parallel spaced ribs 91 and 92 which may be formed integrally therewith when the members 27 and 28 are cast. A pair of identical blocks 93a and 93b are slidably mounted in the longitudinal recesses formed by the ribs 91 and 92 and are adapted to slide longitudinally with respect thereto. The blocks 93a and 93b support a tubular axle 94 and are provided with collars 95.

A pair of identical uniform rise cams 96 are mounted upon the tubular axle 94 and, as illustrated in Figure 6, they engage members 97 and 98. The member 97 is mounted in a boss 99 for longitudinal movement with respect to the member 28. It may be retained in a predetermined position by the nut 101 which is threadedly mounted thereon and which is adapted to be urged into tight frictional engagement with one side of the boss 99. The member 98 is similarly mounted in a similar stud 99a and is adapted to be moved longitudinally by a wheel 102 which is threaded thereto. The driven drum pulley 32 is rotatably mounted upon the tubular axle 94 as by means of bushings 103. A handle 104 is mounted on and keyed to the axle 94. The handle 104 is provided with a pawl-like member 106 which is pivoted thereto as at 107 and whose operative portion 108 is adapted to engage a slot in member 95. The pawl 108 is normally urged into engagement with the slot in member 95 by the spring 110.

The tubular axle 94 also accommodates a spring 111, one end of which is secured to a stub shaft 112 which is keyed to the block 93b by a pin 113 which engages the collar 95 on member 93b. The other end of the spring 111 is secured to a stub shaft 114 which is keyed to the axle 94. Thus we provide an assembly consisting of the axle 94 and the two cams 96 and the stub shaft 114 which rotate as a unit within the blocks 93. The block 93b and the member 112 engaged by pin 113 also form a unit and these two units are operatively connected by the spring 111. Thus torsion on the spring 111 will be transmitted through the shaft 114 and the axle 94 to the cams 96 urging them into engagement with the members 97 and 98. As indicated in Figure 7 this will tend to urge the axle 94 upwardly as viewed in Figures 6 and 7. However by operation of the handle 104 the cams 96 are rotated to the flat on the cams with the result that the axle 94 and the drum 32 will be brought downwardly as viewed in Figures 6 and 7.

Operation of the device may briefly be described as follows: Let it be assumed the belt 33 is new. As is known, new belts are stiff. In our device pulley 32 will be urged upwardly into positions illustrated in Figures 6 and 7 by virtue of the effect of the torque of the spring 111 on the axle 94, and thus on the cams 96, with a force sufficient to produce driving friction of the pulley 31 on the stiff belt 33 without producing an overload on the driving mechanism 19 as shown in Figure 1. Then let it be assumed that as the belt 33 wears it stretches. The same torque of the spring 111 turns the cams 96 to urge the pulley 32 upwardly to compensate for this wear and stretching of the belt 33. Then let it be assumed that the belt 33 has become worn and must be replaced. By operating the handle 104 counterclockwise until the pawl 108 drops into the slot in member 93a due to the force exerted by spring 110 the cams 96 will have been rotated to their flat or low areas as viewed in Figure 7 with the result that axle 94 and the blocks 93a and 93b may be moved downwardly as viewed in Figure 7. The belt 33 may then be removed. While the pulley 32 is in this retracted position a new belt may be put on the device. The handle 104 may then be released by depressing member 106 and thus lifting pawl 108 as viewed in Figure 8 in which event the torsion of the spring 111 will tend to ro-

tate the knob 104 and the axle 94 with the cams 96 as viewed in Figure 7 with the result that the pulley 32 will be moved upwardly as viewed in Figures 6 and 7. The member 111 is a torsion spring. Initial torque load is applied

- 5 by turning handle 104 counterclockwise with belt 33 removed until the desired load is reached. Thus the torsion of spring 111 may be varied. In addition the amount of rise of the uniform rise cams 96 permits accommodation of different lengths of belts on the same device.
- 10 It will be noted that we have also provided means for adjusting the members 97 and 98 against which the cams 96 bear. For example, the member 97 may be pre-set at the factory or at any time when the belt 33 is removed. The member 97 may be slid longitudinally with respect to
- 15 the boss 99 and held in a predetermined position by the member 101. Rotation of member 101 is prevented by trapping it in a pocket cast in the side member adjacent the top of the member 99. In order to prevent rotation of the member 97 we have provided a pin 116 which slides in the slot member 117 as the member 97 is moved upwardly or downwardly. A similar pin 116a reciprocates in a similar slot 117a and prevents rotation of the member 98 when the member 102 is rotated. By proper positioning of the members 97 and 98 the belt 33 may be centered with respect to the pulley 32.

Member 102 is externally adjustable to permit adjustment of belt centering or tracking while the machine is in operation.

- 20 As the belt 33 accommodates itself to the pulleys, the spring 111 will urge the pulley 32 upwardly and maintain proper tension on the belt for correct drive. Moreover, when the cams 96 are actuated the belt setting determined by adjustment of members 97 and 98 is not disturbed.

25 Thus we have provided a simple device which prevents overloading of the drive yet which maintains sufficient tension on the belt at all times to insure driving of the belt by the pulley 31. We have also provided a resilient support to take up or compensate for belt stretch or accommodation of the belt to the device as it wears or becomes more flexible. Differences in original belt lengths is also provided for by our automatic tensioning mounting for the pulley 32.

We claim:

1. In a device of the character described in which a pair of pulleys are rotatably mounted in a frame, one of said pulleys being mounted in bearings which are fixed in said frame, the other of said pulleys being mounted on a hollow axle supported in blocks which are slidably mounted in said frame, a torsion spring in said axle, one end of said spring being operatively connected to one of said blocks and the other end of said spring being operatively connected to said axle, a pair of cams fixed on said axle, which are adapted to engage said frame and to releasably urge said axle and said blocks in a predetermined direction along said frame.

2. In a device of the character described in which a sanding belt is supported by pulleys supported in a frame, one of said pulleys being mounted in bearings which are fixed in said frame, the other of said pulleys being rotatably mounted on an axle which is rotatably mounted in blocks, said blocks being slidably mounted in said frame, a torsion spring in said axle, one end of said spring being secured to one of said blocks and the other end of said spring being operatively connected to a pair of cams which are fixed on said axle and adapted to engage said frame whereby when said cams engage said frame said blocks and drum are urged to a position remote from the other of said drums.

3. In a belt sander construction, a sanding belt, a frame, a pair of pulleys associated with said frame and adapted to support said sanding belt, a pair of blocks slidably mounted in said frame, an axle rotatably mounted in said blocks, one of said pulleys being rotatably mounted in said axle, cam means fixedly mounted on said axle and adapted to engage said frame, the position of said blocks being re-

sponsive to the rotation of said cam means, means for rotating said cam means consisting of a torsion spring, one end of which is fixed to one of said blocks and the other of which is operatively connected to said axle, and handle means on said axle whereby the effect of said spring may be overcome and said axle and said blocks be moved in a direction opposite to that in which the same are normally urged by said cam means under the influence of said spring.

4. In a belt sander construction, a sanding belt, a frame, a plurality of pulleys adapted to support said sanding belt, an axle slidably mounted in said frame, a pair of cams fixedly mounted on said axle and adapted to engage said frame, means for rotating said cams, said axle being responsive to the rotation of said cams, means for rotating said cams consisting of a torsion spring one end of which is in operative engagement with said frame and the other of which is fixed to said cams, and means connected with said axle whereby the effect of said spring may be overcome and said axle moved in a direction opposite to that in which the same are normally urged by said spring.

5. In a belt sander construction, a sanding belt, a frame, a plurality of pulleys adapted to support said belt, an axle supporting one of said pulleys and movably mounted in said frame, a pair of cams fixed on said axle, adjustable means on said frame adapted to be engaged by said cams, means for rotating said cams consisting of a torsion spring one of whose ends is in operative engagement with said cams.

6. In a belt sander construction, a sanding belt, a frame, a plurality of pulleys adapted to support said belt, an axle supporting one of said pulleys movably mounted in said frame, a pair of cams fixedly mounted on said axle, said axle being responsive to the rotation of said cams, adjustable means on said frame and adapted to be engaged by said cams and means for rotating said cams consisting of a torsion spring one of whose ends is in operative engagement with said cams.

7. In a device of the character described in which a pair of pulleys are rotatably mounted in a frame, one of said pulleys being mounted in bearings which are fixed in said frame, the other of said pulleys being mounted on a hollow axle supported in blocks which are slidably mounted in said frame, a torsion spring in said axle, one end of said spring being operatively connected to one of said blocks and the other end of said spring being fixedly connected to said axle, a pair of adjustable members mounted on said frame, a pair of cams fixed on said axle adapted to engage said adjustable members and to releasably urge said axle and said blocks in a predetermined direction along said frame.

8. In a belt sander of the type in which a sanding belt is mounted upon pulleys which are supported in a frame assembly, a pair of similar parallel side members forming a portion of said frame assembly, each of said side members being provided with a plurality of sockets, the

5 sockets in each of said side members being parallel to the path of movement of said belt and opposite pairs of sockets on opposite frame members being at right angles to said path, all of said sockets being so formed that the distances between their centers are equal, a table construction comprising a table and a pair of mounting tubes, means for tilting said table with respect to said mounting tubes, means associated with said sockets to lock said mounting tubes in a predetermined position in said sockets whereby the position of the edge of said table adjacent said belt may be adjusted in accordance with the tilt of said table.

10 9. In a belt sander of the type in which a sanding belt is mounted upon pulleys which are supported in a frame assembly, a pair of similar parallel side members forming the sides of said frame assembly, each of said side members being provided with a plurality of sockets, the sockets in each of said side members being parallel to the path of movement of said belt and opposite pairs of sockets on said frame members being at right angles to said path, a table construction comprising a table and a pair of mounting tubes, means for tilting said table with respect to said mounting tubes, set screws associated with said sockets to lock said mounting tubes and said table in a predetermined position in said sockets, whereby the position of said table with respect to said belt may be adjusted.

15 20 10. In a belt sander of the type in which a sanding belt is mounted upon pulleys which are supported in a frame assembly, a pair of parallel side members forming the sides of said frame assembly, each of said side members being provided with a pair of sockets, the pairs of sockets in each of said side members being parallel to the path of movement of said belt and opposite pairs of sockets in said frame members being at right angles to said path, a table construction comprising a table, a frame for said table and a pair of tubes, a table being tiltable with respect to said frame, the pair of tubes adapted to engage selected pairs of said sockets, the tubular members being adapted to be engaged in said sockets in a predetermined position whereby the position of the edge of said table adjacent said belt may be set at a predetermined distance from said belt regardless of the degree of tilt of said table.
